WALL SUPPORT

Charles W. Dunlap, Chicago, Ill., assignor to Plibrico Jointless Firebrick Company, Chicago, Ill., a corporation of Illinois

Application November 10, 1938, Serial No. 239,778

5 Claims. (Cl. 72—101)

This invention relates to supporting means, and has to do with means for supporting linings for furnace walls and analogous structures.

My invention is directed to supporting means of the character stated comprising a shelf-like member and a cooperating anchor member intended for securement in a wall, the anchor member having simple and highly efficient means whereby it may be secured in position with expedition and facility.

More specifically, the anchor is so constructed as to provide highly efficient means for supporting, at its inner end, a cooperating member, the anchor being provided at its outer end with elements adapted for cooperation with a securing member or for cooperation with the corresponding element of a similar anchor member, whereby a variety of conditions encountered in practice may be met in simple and efficient manner. Further objects and advantages will appear from the detail description.

In the drawings:

Figure 1 is a side view of a wall anchor embodying my invention;

Figure 2 is a side view of a shelf member intended for mounting on the anchor of Figure 1;

Figure 3 is a plan view of the wall supporting means, comprising the anchor and the shelf disposed in assembled relation;

Figure 4 is a fragmentary inner face view of a lining formed in sections and supported by the supporting means of Figure 3;

Figure 5 is a fragmentary vertical sectional view through a wall and a lining therefor, showing a wall anchor and a lining supporting member applied in accordance with my invention, this view being taken substantially on line 5—5 of Figure 6;

Figure 6 is a sectional view taken substantially on line 6—6 of Figure 5, the wall anchor and the securing means therefor, as well as the shelf member being shown in plan;

Figure 7 is a fragmentary vertical sectional view through an inner wall of a furnace construction provided with a lining at each side, showing two oppositely disposed wall anchors arranged in interengaging relation one with the other, this view being taken substantially on line 7—7 of Figure 8;

Figure 8 is a sectional view taken substantially on line 8—8 of Figure 7, the wall anchors and associated elements being shown in plan;

Figure 9 is a sectional view on the order of Figure 5, taken substantially on line 9—9 of Fig-

ure 10, but showing a different construction of furnace wall;

Figure 10 is a sectional view taken substantially on line 10—10 of Figure 9, the wall anchors and associated parts being shown in plan;

Figure 11 is a sectional view on the order of Figure 7, taken substantially on line 11—11 of Figure 12, but showing modified means for securing together the wall anchors; and

Figure 12 is a sectional view taken substantially on line 12—12 of Figure 11, the wall anchors and associated parts being shown in plan.

The wall anchor and associated shelf member are shown more clearly in Figures 1 to 3, inclusive. The wall anchor comprises a body 15 of elongated rectangular shape in plan provided at one end, which may be termed the inner end for purposes of description, with an integral depending flange 16. An upwardly tapering stud 17 of frusto-conical shape is integrally connected to flange 16 and spaced inward therefrom by a web element 18, the upper portion of which extends outward along the upper face of body 15 centrally thereof. Stud 17 is provided with a lower base flange 19 projecting radially outward thereof. A shelf member 20, conveniently of rectangular shape in plan, is provided, adjacent its outer side, with an integral depending socket member 21 from which extend reinforcing ribs 22 projecting radially from socket member 21 and tapering upward in height, these ribs being integral with the shelf and the socket member. Socket member 21 is open at both its upper and its lower ends and defines an interior upwardly tapering socket 23, which is somewhat larger than the stud 17, socket member 21 also being provided with an outwardly flaring lengthwise slot 24 at the outer side of shelf member 20. The width of slot 24 is appreciably greater than the transverse thickness of web element 18, thus providing clearances between the side walls of slot 24 and the web element 18. When the shelf member 20 is applied to stud 17, as in Figure 3, it rests upon base flange 19 of the stud and is free from the latter for relative movement both lengthwise and transversely, due to the clearance provided by the socket 23, whereby the shelf member is capable of movement relative to stud 17 for accommodating expansion and contraction of the lining supported by the shelf member, as will be described more fully later.

Body 15 of the anchor is provided at its other end portion, which may be termed its outer end for purposes of description, with a lengthwise slot 25 forming two parallel arms 26 of equal width.

Body 15 of the anchor is provided at its other end portion, which may be termed its outer end for purposes of description, with a lengthwise slot 25 forming two parallel arms 26 of equal width.

Each arm 26 is provided, at its outer end, with an upwardly extending flange element 27 of greater width than the associated arm and projecting beyond the inner and the outer edges of the arm. Each flange element 27 preferably is connected to the associated arm 26, adjacent the inner edge thereof, by an integral fillet element 28.

The anchor and the shelf member of Figures 1 to 3, inclusive, are particularly suitable for supporting a refractory lining for a furnace wall or other structure, though they may be used to advantage for other purposes. In Figure 4 I have shown fragmentarily a refractory lining anchored to a wall by suitable anchor means *a* of a character to permit expansion and contraction of the lining in all directions in a plane parallel to the inner face of the associated wall, the anchor means *a* preferably being of the character disclosed in Patent No. 1,828,618, issued October 20, 1931, to Ivon S. Pieters, for Anchor for furnace lining. Lining L is initially formed from plastic material and is constructed in monolithic form, being later separated into sections *l* which may expand and contract individually, with the object of avoiding stresses such as would occur if the lining were of considerable extent and of monolithic structure. Each of the sections *l* of the lining L rests upon a suitable number of shelf members 20 so as to be supported thereby, each of the shelf members being mounted upon a wall anchor in the manner above described.

In Figures 5 and 6 I have shown a brick wall W, which may be considered as the setting or casing wall of a furnace, at the inner face of which is disposed a lining L of refractory material, such as that above referred to, such lining being separated into sections *l*. Each section *l* of the lining is supported by a suitable number of shelf members 20, each mounted upon a wall anchor imbedded in the wall W, flange 16 of this anchor extending downward from body 15 thereof and seating against the inner face of the furnace wall. A securing member, conveniently in the form of a bolt 30, extends between flange elements 27 at the outer end of body 15 of the anchor, this bolt being provided at its inner end with a squared head 31 which engages in front of the inner edge portions of flange elements 27, the shank of bolt 30 passing through a slot 32 between the inner edges of the flange elements. Bolt 30 extends outward beyond wall W, a suitable distance, and receives a nut 33 screwed thereon, there being a washer 34 interposed between this nut and the outer face of the furnace wall. In cases where a stay is disposed at the outer face of the furnace wall, as is commonly done, bolt 30 may be passed through the stay, upon the outer face of which the nut 33 may seat, as will be obvious. The flange elements 27 and bolt 30 provide simple and efficient means for securing the anchor in position in wall W.

Referring further to Figure 3, it will be noted that the width of slot 25 is slightly greater than the width of the respective flange elements 27, and the width of slot 32 is slightly greater than the width of the respective arms 26 but is considerably less than the width of the respective flange elements 27. Due to that arrangement, a second wall anchor similar to that shown in Figures 1 and 3 may be readily attached to the outer end of the latter wall anchor, by inserting one arm 26 of the second anchor through slot 32 of the first anchor, so that a flange element 27 of the second anchor is disposed in overlapping relation

to the flange elements 27 of the first anchor. That may be accomplished either by moving the arm 26 of the second anchor downward through slot 32 of the first anchor, or by inserting one flange element 27 of the second anchor through slot 25 of the first anchor, moving arm 26 of the second anchor upward through slot 32 of the first anchor.

In Figures 7 and 8, there is shown a wall W¹ of brick construction which may be considered as a center or an intermediate wall of a furnace construction, in which combustion chambers are provided at opposite sides of wall W¹. This latter wall is provided, at each side thereof, with a refractory lining L divided into sections *l*. These sections of the lining are supported by shelf members 20, as before. The wall W¹ is of considerably less thickness than the wall W of Figures 5 and 6, being approximately eight inches in thickness, it being noted that the body 15 of the wall anchor is approximately four inches in length, usually somewhat greater. In the construction of Figures 7 and 8, the wall anchors are arranged in pairs, with a flange element 27 of one anchor disposed in overlapping relation to the flange elements 27 of the other anchor, and an arm 26 of the first anchor extending through slot 32 of the second anchor, as shown in Figure 8. In that manner the two wall anchors are effectively locked together so as to be held against relative movement toward the sides of wall W¹. The anchors secured together in this manner support the shelf members 20, the latter supporting the sections *l* of the lining L, in the manner previously described.

In the construction shown in Figures 9 and 10, wall W² comprises an inner portion *w* formed of hollow tile, a coating *w*¹ of suitable thermal insulating material and a sheet metal sheathing *w*². Sections *l* of lining L, at the inner face of wall W², are supported by shelf members 20 mounted upon wall anchors imbedded in wall W², each of these anchors being secured against inward movement by a headed bolt 35, upon the outer end of which is threaded a nut 36 bearing against the outer face of sheathing *w*².

The construction shown in Figures 11 and 12 is quite similar to that shown in Figures 7 and 8, except that the wall W³ is considerably thicker than wall W¹, being approximately twelve inches in thickness. Assuming that the body portions of the wall anchors are approximately four inches in length, or somewhat greater, it will be apparent that when two anchors are imbedded in wall W³ in alignment, with flanges 16 disposed at the opposite sides of the wall, the ends of these anchor members carrying the flange elements 27 will be spaced a considerable distance apart. Under such conditions, the adjacent ends of the anchor members may be secured together with expedition and facility by means of a bolt 38, provided at one end with a squared head 39 and having a squared nut 40 threaded onto its other end, the shank of this bolt passing through the slots 32 of the aligned anchors, with head 39 in overlapping relation to flange elements 27 of one of the anchors and nut 40 in overlapping relation to the flange elements of the other anchor.

It will be seen, from what has been said above, that the wall supporting means of my invention is particularly suitable for use with walls of various constructions and thicknesses, and that the anchor member is readily adaptable to various conditions of use, such as are frequently encountered in practice. Within the broader con-

cepts of my invention, the anchor member may be used for supporting either a shelf member or any other desired member, to suit requirements. It will be understood that changes in construction and arrangement of parts of my invention may be resorted to, without departing from the field and scope thereof, and I intend to include all such variations, as fall within the scope of the appended claims, in this application in which the preferred forms only of my invention have been disclosed.

I claim:

1. In a furnace structure, a wall, a refractory lining therefore, anchors secured in said wall each comprising a body having at its inner end a depending flange and an upwardly tapering stud carried by and spaced from said flange, said anchor having at its outer end upwardly extending spaced flange elements, means secured to said wall and engaging said flange elements of the respective anchors for restraining the latter against inward movement, and shelf members each provided at its outer side with an upwardly tapering socket element loosely receiving said stud, said shelf members extending inward from said studs beneath said lining for supporting the latter.
2. In a furnace structure, a wall, a refractory lining therefor, wall anchors each comprising a body provided at its outer end with spaced upwardly extending flange elements, shelf members, each of the latter and said body of the respective anchors, at its inner end, having cooperating means for supporting said shelf member for relative universal movement while limiting relative downward movement thereof, and means cooperating with said flange elements for restraining the respective anchors against inward movement.

3. In a furnace structure, a wall, refractory linings at opposite sides of said wall, pairs of wall anchors each comprising a body provided at one end portion with two spaced arms each having an upwardly extending flange element of appreciably greater width than the associated arm, an arm of one anchor of the respective pairs being disposed between the flange elements of the other anchor with the associate flange element of said arm of said one anchor in overlapping relation to said flange elements of said other anchor, and shelf members at the other ends of the respective wall anchors for supporting said linings, said shelf members and said anchors, at said other ends thereof, having cooperating means for supporting said shelf members.

4. In supporting means of the character described, a wall anchor comprising a body provided at its outer end with upwardly extending flange elements spaced apart for receiving between them a securing member, and a shelf member, the latter and said anchor, at its inner end, having cooperating means for supporting said shelf member.

5. As a new article of manufacture, a wall anchor comprising a body provided at its outer end with two spaced arms each having a flange element substantially perpendicular thereto and of appreciably greater width than the associated arm, the inner edges of said flange elements being spaced apart for reception therebetween of an arm of a second similar anchor with the associated flange element of said arm of said second anchor disposed in overlapping relation to said flange elements of said first anchor.

35

CHARLES W. DUNLAP.
